UNITED STATES PATENT OFFICE.

ANDREW J. BERRIEN, OF TRENTON, NEW JERSEY, ASSIGNOR OF ONE-HALF TO
PIERCE-ROBERTS RUBBER CO., OF TRENTON, NEW JERSEY, A CORPORATION
OF NEW JERSEY.

BATTERY FILLER.

Application filed September 19, 1925. Serial No. 57,370.

This invention relates to certain improvements in battery fillers and it is an object of the invention to provide a device of this general character comprising a cap adapted to be applied over the neck of a bottle or kindred container and which is provided with an elongated discharge spout and with a vent, the closing of the vent stopping flow through the spout.

10 Another object of the invention is to provide a device of this kind preferably formed of molded rubber and which can be readily applied or removed as the occasions of practice may necessitate.

15 The invention consists in the details of construction and in the combination and arrangement of the several parts of my improved battery filler whereby certain important advantages are attained and the device 20 rendered simpler, less expensive and otherwise more convenient and advantageous for use, as will be hereinafter more fully set forth.

The novel features of my invention will 25 hereinafter be definitely claimed.

In order that my invention may be the better understood, I will now proceed to describe the same with reference to the accompanying drawings, wherein:—

30 Figure 1 is a view in elevation illustrating a battery filler constructed in accordance with an embodiment of my invention and in applied position with the coating receptacle in pouring adjustment;

35 Figure 2 is a view in elevation of the device as herein disclosed applied but in an upright position;

40 Figure 3 is a vertical sectional view taken through the device as illustrated in Figure 2 unapplied.

As disclosed in the accompanying drawings, my improved device comprises a cap C of molded rubber adapted to be applied over the neck N of a bottle or kindred receptacle 45 containing distilled water and extending outwardly from the peripheral portion of the outer closed end 1 of the cap C is an elongated spout 2 integral with the cap C. This spout 2 has its bore 3 continued by the bore of a nipple 5 extending within the upper portion of the cap C, the inner or free end of said nipple being closed and said nipple immediately adjacent to its free or closed end being provided with an opening 55 or port 6 facing the open end of the cap C.

Diametrically opposed to the spout 2, the closed end 1 of the cap C is provided therethrough with a vent opening 7 which is also continued through an outstanding boss 8 integrally formed with said end 1.

The cap C immediately adjacent to its closed end 1 is provided with an internal continuous flange 9 and extending entirely around the side wall 10 of the cap C so that said portion of the cap is strengthened and at the same time providing a shoulder for contact with the outer edge of the neck N whereby to prevent the cap from being forced too far downward upon the neck of the bottle.

In practice, the cap C is applied to the neck N of a bottle or kindred receptacle containing distilled water and in filling a battery the forefinger of the hand grasping the bottle or receptacle is placed upon the boss 8 closing the vent 7 and thereby stopping flow through the spout 2 and particularly when the bottle or other receptacle is in pouring position and thus readily permitting the spout 2 being moved from one battery cell 80 to another without spilling water over the battery. By lifting the finger from the boss 8 requisite flow will be had through the spout 2 to effect the desired filling of the battery cell.

I claim:—

1. As an article of manufacture, a hollow bottle cap of flexible resilient rubber having a closed end and a side wall, said cap being adapted to be applied over the neck of a water-containing bottle, a spout integral with the cap and extending outwardly from the cap, and the closed end of the cap having an outstanding boss formed with a vent passing to the interior of the bottle.

2. As an article of manufacture, a battery filling device comprising a hollow cap of flexible resilient rubber formed to provide a closed end and a side wall and adapted to be applied over the neck of a water-containing receptacle, the cap being formed with a spout extending outwardly at an inclination to the longitudinal axis of the cap and from the marginal portion of the closed end and in communication with the interior of the cap, said closed end of the cap being provided with a boss upon the end face thereof and with a vent extending through this boss to the interior of the cap, the cap being provided with an internal shoulder extending

around the side wall of the cap immediately adjacent the closed end thereof, the inner wall of the shoulder being disposed exteriorly of the inner end of the vent whereby to prevent the vent from being closed by the extremity of a water containing receptacle.

3. As an article of manufacture, a battery filling device comprising a cap of flexible resilient rubber formed to provide a closed 10 end and a side wall and adapted to be applied over the neck of a water-containing receptacle, the cap being formed with a spout extending outwardly from the marginal por-

tion of the closed end and in communication with the interior of the cap, said closed end 15 of the cap being provided with a boss upon the exterior face thereof and with a vent extending through this boss to the interior of the cap, said spout being continued by a nipple extending within the cap and provided with an admission opening directed 20 away from the vent.

In testimony whereof I hereunto affix my signature.

ANDREW J. BERRIEN.
